(57) **CLAIM**

The ornamental design for a gutter guard, as shown and described.

DESCRIPTION

FIG. 1 is a perspective view of a first embodiment of a gutter guard;

FIG. 2 is another perspective view of the gutter guard of FIG. 1;

FIG. 3 is a left-side elevation view of the gutter guard of FIG. 1;

FIG. 4 is a right-side elevation view of the gutter guard of FIG. 1;

FIG. 5 is a rear elevation view of the gutter guard of FIG. 1;

FIG. 6 is a front elevation view of the gutter guard of FIG. 1;

FIG. 7 is a top plan view of the gutter guard of FIG. 1;

FIG. 8 is a bottom plan view of the gutter guard of FIG. 1;

FIG. 9 is a perspective view of a second embodiment of a gutter guard;

FIG. 10 is another perspective view of the gutter guard of FIG. 9;

FIG. 11 is a left-side elevation view of the gutter guard of FIG. 9;

FIG. 12 is a right-side elevation view of the gutter guard of FIG. 9;

FIG. 13 is a rear elevation view of the gutter guard of FIG. 9;

FIG. 14 is a front elevation view of the gutter guard of FIG. 9;

FIG. 15 is a top plan view of the gutter guard of FIG. 9;

FIG. 16 is a bottom plan view of the gutter guard of FIG. 9;

FIG. 17 is a perspective view of a third embodiment of a gutter guard;

FIG. 18 is another perspective view of the gutter guard of FIG. 17;

FIG. 19 is a left-side elevation view of the gutter guard of FIG. 17;

FIG. 20 is a right-side elevation view of the gutter guard of FIG. 17;

FIG. 21 is a rear elevation view of the gutter guard of FIG. 17;

FIG. 22 is a front elevation view of the gutter guard of FIG. 17;

FIG. 23 is a top plan view of the gutter guard of FIG. 17;

FIG. 24 is a bottom plan view of the gutter guard of FIG. 17;

FIG. 25 is a perspective view of a fourth embodiment of a gutter guard;

FIG. 26 is another perspective view of the gutter guard of FIG. 25;

(Continued)

FIG. 27 is a left-side elevation view of the gutter guard of FIG. 25;
 FIG. 28 is a right-side elevation view of the gutter guard of FIG. 25;
 FIG. 29 is a rear elevation view of the gutter guard of FIG. 25;
 FIG. 30 is a front elevation view of the gutter guard of FIG. 25;
 FIG. 31 is a top plan view of the gutter guard of FIG. 25; and,
 FIG. 32 is a bottom plan view of the gutter guard of FIG. 25.
 FIGS. 17-18, 21-26, and 29-32 include symbolic breaks along the length. The area between the break lines forms no part of the claimed design. The broken lines depict portions of the gutter guard that form no part of the claimed design.
